P. ZARS ET AL

SWITCHING DEVICE FOR ELECTRIC CIRCUITS

Filed Sept. 17, 1921

FIG. 1.

Inventors:

Paul Zars
Spenc. & G. Inc.

UNITED STATES PATENT OFFICE.

PAUL ZARS, OF DUSSELDORF-GRAFENBERG, AND SVEND DYHR, BERLIN-CHARLOTTENBURG, GERMANY, ASSIGNORS TO DEUTSCHE SCHWEISSMASCHINENFABRIK BECKER & CO. A.-G., OF BERLIN-SCHONEBERG, GERMANY.

SWITCHING DEVICE FOR ELECTRIC CIRCUITS.

Application filed September 17, 1921. Serial No. 501,220.

To all whom it may concern:

Be it known that we, PAUL ZARS and SVEND DYHR, citizens of Germany and Denmark, respectively, residing at Dusseldorf-Grafenberg, Germany, and Berlin-Charlottenburg, Germany, respectively, have invented certain new and useful Improvements in Switching Devices for Electric Circuits, of which the following is a specification.

This invention relates in general to switching devices and more particularly to devices of this kind which intermittently open or close an electric circuit or circuits in quick succession.

In mechanical devices of this kind the rapid blows of the circuit-closing members or contacts on each other give rise to disturbing noises, and the springs used hitherto for damping the blows and reducing the concussion produce undesirable secondary vibrations of the contacts.

It is an object of this invention to remove these drawbacks. This is accomplished by positively moving or guiding the cooperating contacts relatively to each other.

In the drawings affixed to this specification and forming part thereof our invention is illustrated diagrammatically by way of example. In the drawings—

Fig. 1 shows an oscillating make-and-break switch whose contact-making members are moved by cams or eccentrics driven by a shaft,

Fig. 2 shows a similar switch with cushioned contacts, and

Fig. 3 illustrates a third form of a contact in accordance with this invention.

In Fig. 1, *a* designates a base plate consisting of an insulating substance and *b*, *c*, *d* are metal brackets to each of which a leaf spring *e*, *f*, and *g* respectively is attached. Each of these springs is an electrical conductor connected to a wire *x*, *y* and *z* respectively and carries a contact *h*, *i* and *k* respectively adapted to open and close an electric circuit. Attached to each of these contacts is a member *l*, *m* and *n* respectively which may be resilient and carries a clamping device *o*, *p* and *q* respectively at its upper end. The two clamping devices *o* and *q* are fastened to a common rod *r*, while the clamping device *p* is fixed to another rod *s*. Each of these two rods *r* and *s* is linked

to a cam or the like as *t* and *u* respectively arranged on a common shaft *w*.

When the shaft *w* rotates the rods *r* and *s* move to and fro, one of them oscillating the contacts *h* and *k*, and the other *s* oscillating the contact *i*. By proper adjustment of the two eccentrics *t* and *u* with respect to each other the contacts can be made to close and open their respective circuits in any desired manner. The striking of the contacts against each other causes only very little noise and the undesirable secondary vibrations of the contacts are practically eliminated.

The switching device described in the preceding paragraph is a make-and-break switch in which the current supplied to the middle contact *i* is sent through the two outer contacts *h* and *k* alternately. If one of the outer contacts *h* or *k* were omitted the device could be employed as a simple interrupter.

A feature of the invention consists in its being possible to regulate the duration of the intervals of closure or interruption of the circuits by shifting the clamping devices *o*, *p* or *q* on the rods *r* or *s*.

If the members *l*, *m* and *n* are made rigid instead of resilient the clamping devices *o*, *p* and *q* must be made resilient or in the form of movable joints so as to permit of variations of the distances between the contact carrying members.

Instead of operating the contacts *h*, *i* and *k* by control gear that is completely positive in action, the arrangement could be such that the contacts *h*, *i* and *k* are coupled to the rods *r* and *s* only in certain positions of their travel.

The contact supports *e*, *f* and *g* may be made rigid instead of resilient and joined to the brackets *b*, *c* and *d* by hinges.

Instead of making the members *l*, *m* and *n* resilient that connect the contacts *h*, *i* and *k* to the eccentrics *t* and *u*, spring members may be inserted in the rods *r* and *s*.

The contacts *h* and *k* need not be driven by a common eccentric *t*, but in accordance with another feature of the invention a separate eccentric or the like may be used for each contact.

Another feature of the invention consists in making the contacts of the device of bodies consisting of copper wire (such as the

gauze used for dynamo brushes) for the purpose of reducing noises caused by the contacts striking against each other.

- A device with an oscillating cushioned contact arranged between two lateral contacts is shown in Fig. 2. The middle contact comprises the support i_1 , a soft intermediate piece i_2 consisting, say, of copper gauze, and the two contact caps i_3 and i_4 . One of the two counter contacts comprises a support h_1 , the soft intermediate body h_2 and the cap h_3 , while the other counter contact comprises the support h_4 , the soft intermediate piece h_5 and the cap h_6 . Thus in this device the gauze bodies h_2 , i_2 and h_5 do not make and break the contacts themselves, but only act as conducting, sound-damping or muffling members associated with the contact-making parts h_3 , i_3 , i_4 and h_6 . In Fig. 3 h_4 is a contact support and h_5 a contact of copper gauze that makes and breaks contact itself.

The bodies of copper gauze may, of course, be replaced by bodies consisting of small bundles of wire or the like.

We wish it to be understood that we do not desire to be limited to the exact details of construction shown and described, for obvious modifications will occur to a person skilled in the art.

We claim:

1. A switching device for electric circuits comprising, a plurality of cooperating contacts, a primary cam for positively actuating some of the said contacts, a secondary cam for positively actuating another of the said contacts, and resilient connecting members between the said cams and the said contacts.

2. A switching device for electric circuits comprising, a plurality of cooperating contacts, a primary positively-operating driving means for actuating one of the said contacts, a secondary positively-operating driving means for actuating another of the said contacts, and means for regulating the intervals of closure of the cooperating contacts.

3. A switching device for electric circuits comprising, a plurality of cooperating contacts, a plurality of separate driving means, one for each said contact, and means for regulating the intervals of closure of the cooperating contacts.

4. A switching device for electric circuits comprising, a plurality of cooperating contacts, a primary cam for positively actuating some of the said contacts, a secondary cam for positively actuating another of the said contacts, and means for regulating the intervals of closure of the cooperating contacts.

5. A switching device for electric circuits comprising, a plurality of cooperating contacts, a primary positively-operating driving means for actuating one of the said contacts,

a secondary positively-operating driving means for actuating another of the said contacts, resilient connecting members between the said driving means and the said contacts, and means for regulating the intervals of closure of the cooperating contacts.

6. A switching device for electric circuits comprising, a plurality of cooperating contacts, a primary cam for positively actuating some of the said contacts, a secondary cam for positively actuating another of the said contacts, resilient connecting members between the said cams and the said contacts, and means for regulating the intervals of closure of the cooperating contacts.

7. A switching device for electric circuits comprising, a plurality of cooperating contacts, cams, motion-transmitting members adapted to be actuated by the said cams, and coupling members for coupling the contacts to the motion-transmitting members, the positions of the coupling members being adjustable relatively to each other, whereby the intervals of closure of the said cooperating contacts may be regulated.

8. A switching device for electric circuits comprising, a plurality of cooperating sound-deadening contacts, a primary positively-operating driving means for actuating one of the said contacts, a secondary positively-operating driving means for actuating another of the said contacts, and resilient connecting members between the said driving means and the said contacts.

9. A switching device for electric circuits comprising, a plurality of cooperating sound-deadening contacts, a primary cam for positively actuating some of the said contacts, a secondary cam for positively actuating another of the said contacts, and resilient connecting members between the said cams and the said contacts.

10. A switching device for electric circuits comprising, a plurality of cooperating sound-deadening contacts, a primary positively-operating driving means for actuating one of the said contacts, a secondary positively-operating driving means for actuating another of the said contacts, and means for regulating the intervals of closure of the cooperating contacts.

11. A switching device for electric circuits comprising, a plurality of cooperating contacts, a primary positively-operating driving means for actuating one of the said contacts, and a secondary positively-operating driving means for actuating another of the said contacts, the said contacts comprising, sound-deadening members of divided yielding metal.

12. A switching device for electric circuits comprising, a plurality of cooperating contacts, a primary positively-operating driving means for actuating one of the said contacts, and a secondary positively-operat-

ing driving means for actuating another of the said contacts, the said contacts comprising, sound-deadening members of copper gauze.

5 13. A switching device for electric circuits comprising, a plurality of cooperating contacts, a primary positively-operating driving means for actuating one of the said contacts, and a secondary positively-operat-

ing driving means for actuating another of the said contacts, the said contacts comprising, sound-deadening members of divided yielding metal, and solid contact-making caps.

In testimony whereof we have signed this 15
specification.

PAUL ZARS.
SVEND DYHR.
